UNITED STATES PATENT OFFICE.

FRANZ KRUCKENBERG AND FRITZ GENTZCKE, OF HEIDELBERG, GERMANY; SAID GENTZCKE ASSIGNOR TO SAID KRUCKENBERG.

CAR FOR HIGH-SPEED SUSPENSION RAILWAYS.

Application filed January 24, 1925, Serial No. 4,572, and in Germany November 5, 1924.

The invention concerns a car for a high speed suspension railway attaining a velocity of 200 to 300 miles an hour, having a torpedo shaped body of so-called streamline 5 form. In the arrangement shown the car is suspended from a single rail on which the wheels run and is propelled by one or more air screws.

In the present invention, owing to the necessity of saving weight, the whole hull of the car is shown as a frame-work lightly constructed of longitudinals, diagonals and cross frames. The diagonals can be conveniently replaced by the outer skin of the 15 car. Further, in this invention, in order to maintain the car section crossframes are employed having a passage way through them. Moreover, in this invention the seats for the passengers are conveniently arranged 20 so as to make good use of the available space and the longitudinal stiffening girders. In order to house the wheels of the car and also the brakes and running gear, a long fin or inverted keel is arranged, running along the 25 top of the car which is covered like the rest of the car body. This fin or inverted keel contains at the same time stiffening-members for the car frame-work.

In the drawings are shown several methods of constructing the car and details of the 30 same.

Fig. 1 shows in side-elevation the outline of the car-hull with the inverted keel. The frame-work of the hull is indicated with 35 single lines and the outer covering is removed.

Figs. 2, 3 and 4 show outside views of similar cars and combinations of cars to a 40 smaller scale.

Fig. 4^a is a detail view of the ball joint and buffer which is disposed at 21 of Fig. 4.

Fig. 5 is a section through the hull of 45 Figure 1 on the line A—A.

Fig. 6 shows in sectional elevation the interior of a car to smaller scale and serves among other things to show the static 50 conditions.

Fig. 7 is a section on the line B—B of 55 Figure 1 through the door.

Figs. 8 and 9 are views of the car frame-work in the neighbourhood of the windows.

Figs. 10, 11, 12 and 13 are vertical cross-sectional views of four different types of door closures.

Figs. 14, 15, 16 and 17 are perspective

views, partly in cross-section, of various forms of the beams or rods used to strengthen the car-body.

As Fig. 1 shows, the frame-work of the streamline hull consists of longitudinals 1, 60 verticals 2 and diagonals 3. Rather above the middle line, openings for windows 15 are provided in diagonal frames 4. The members have a profile the flanges of which are curved or "radiused", or a circular profile. 65 (See Figs. 14-17.) The details of these members are more fully described later. The sectional stiffness of the car-hull is provided for by cross-frames 5 (see Figs 1, 5 and 6), which have an opening 6 in the 70 middle such as to allow people to pass through freely. They appear in Fig. 1 as vertical members. Such cross-frames are also provided where the suspension-arms for the wheel work are fastened to the hull. 75 Further the cross-frames serve for dividing up the passenger-seats 8 and for transferring the weight of the passengers to the frame-work (Fig. 6). The seats 8 in this invention are provided along the curved walls of 80 the hull so that the passengers sit with their feet in the middle-gang way while the shape of the outer wall is convenient to lean against. The windows lie above the backs of the seats in the upper part of the curved 85 wall so that the surface of the earth near to the car is out of sight of the passengers. This is necessary in order not to disturb the passenger's sense of safety. With regard to this the parts of the track have no influence 90 owing to their nearness to the car.

Figs. 5 and 6 show the arrangement of the seats and the extent of the passenger's view. The arrangement of the seats is such as to allow the use of deep section and therefore 95 economical longitudinals 9 below the seats giving longitudinal stiffness to the car and serving also to support the seats and the cross-girders 10. These cross-girders support the floor and can be made with a very 100 small height so that the gang-way will not be too low. The space above the seats between the cross frames is used for stowing hand-luggage which rests on the shelves 11.

The section of the carbody is most conveniently not of circular but of elliptic shape (Fig. 5). This elliptic shape offers two special advantages. Firstly the area offered to side wind is smaller and secondly the accommodation of the passengers in a 110

comfortably seated position is possible with the most economical use of the space. This is important for several reasons, one being that the weight of the car and consequently the axle-loads and the cost of the supporting construction are kept as low as possible, another that the air resistance and mass to be accelerated is reduced to a minimum. Since the fin 13 containing the running gear 12 to which is fastened the supporting arm 7 is situated above the hull of the car, the elliptical form of the hull must be joined with the form of the fin by smooth curves, similarly to the connection of a bottle with its neck. By means of this shape the transference of the load is rendered easy while it has a very low air resistance and further the gangway height "h" in Fig. 5 is sufficiently great and also provides enough height for suitable frames to be constructed above the gangway 6. The inverted keel embraces the rail 14 on one side in the form of a hook (Figs. 1 and 5) having a channel along one side which gives the necessary space for the rail. In the keel besides the running-gears 12 and brakework 52, 53 can also be stowed the fuel-, cooling-water-, and oil tanks and also the cooling arrangements and so on.

30 The frame-work of the car must be interrupted in a statically unfavourable manner in order to provide window and door openings 15 and 16. In the case of the windows as shown in Figs. 1 and 9 these disadvantages can be reduced or obviated by continuing the triangular panels by means of the diagonals 4 and 4^a so that the unfavourable effect of the sheer force T in Fig. 8, in which rectangular windows 15^b are shown for comparison, is neutralized.

40 The framework is seriously weakened by the large door opening 16. This difficulty is overcome by means of a stiffening framework 17 above the hull (Fig. 1) for which the keel presents the necessary room and in fact the only possibility (see section of Fig. 7). This stiffening framework 17 serves at the same time to transmit the horizontal forces of wheel and rail brakes to the framework of the car. For this purpose the two supporting arms 7 are connected to the frame-works 17 by the longitudinals 18. Without this connection the brake-force B (see Fig. 6) would put too heavy a bending stress on both the arms 7 and the closed frames 5^a. The covering of the keel 13 can also act as stiffening for the carhull for example by continuing a frame-work over the whole length of the car.

50 A special construction of the car is shown in Fig. 2 consisting of two separate sections coupled closely together. In this case one bogie at the front and one at the rear is all that is necessary for supporting the car. Should however the parts need to be sepa-

rately movable two extra-running gears 12^a are required, which in order to allow curves to be traversed with the two parts coupled together, must be mounted on traverse tables or with an arrangement such that they can be lifted out of contact with the rail. A separation of the parts of the car can be necessitated by need for repairs to the machinery. One can then couple the other part of the car serving as machinery-room or passenger-room or both to a fresh section. The car in Fig. 3 consists of three parts.

When two air screws, one in front and one behind, are used, one of them, preferably the front 19^a of Fig. 3 can be constructed for high thrust especially for starting and slow running. At full speed this air screw can be allowed to run free or may be driven with special revolutions corresponding to its pitch. Both air screws 19 and 19^a can be driven by a common motor or two separate ones. What has been said regarding forward travelling and starting is also applicable to backward travelling and braking. In contrast to Figs. 2 and 3 Fig. 4 shows two cars coupled together from 30-60 feet apart by means of a strut 20. At 21 are arranged ball joints and buffers. Various types of ball joints and buffering devices may be used to couple the cars and the strut 20, and one type of device found suitable is shown in Fig. 4^a. In this device, strut 20 is provided with a slidable sleeve 56 which bears against spring 21^a. The curved part 63 of fin 13 bears against sleeve 56 and the car is thus restrained from forward movement relative to strut 20. Any tendency of the second car to fall behind the first is restrained by the compression of the coil spring mounted on the end of rod 61 against cross-piece 60. This combination comes into force when the frequency of cars can be no longer increased sufficiently for the traffic requirements and the supporting construction is not strong enough to carry a heavier car.

60 The door opening 16 is situated in the sharply curved portion of the outer shell and the closing of the opening presents some difficulties. It shall not increase the air resistance of the car nor interfere with the construction or smoothness of the hull. In this invention two methods of closing the opening have been considered. One consists of flaps that are hinged horizontally the other of a flexible blind which is like a jalousie sliding in rails or channels in the wall of the car. Fig. 10 shows a double-flap form, the lower part 23 hinging on the axis 25 and serving as a foot-bridge 24 in case of emergency, the upper part 26 hinging upwards on the axis 27. The lower part can be fastened to the platform 22 temporarily in order to prevent oscillations of the car as passengers step in and out. If

the car, in order to accelerate the filling and emptying with passengers, is in contact with the platform then the arrangement shown in Fig. 11 is applicable. Here one flap 28 is hinged to the other 29 at the point 30 and the lower point 31 runs (for example) in channels 32 so that the whole arrangement hinging on the fixed axis 33 and the free axis 30 can be moved bodily upwards. 10 The lightest and least cumbrous arrangement is that shown in Figures 12 and 13 of which the latter shows the upper part of the car to an enlarged scale. Here no part of the arrangement projects out of the 15 wall of the car as was the case to a greater or less extent with the two previous methods. The upper part 35 of the channel 34 is hinged at 36 and at the commencement of raising the jalousie 37 this upper part 35 is drawn inwards. But in lowering the jalousie the upper part is pushed outwards, (for example) by the spring 38 so that the opening is completely closed against the ingress of dirt and wet. By turning the roller 25 39 on which the jalousie is wound the connecting band 40 is pulled and both the upper ends 35 of the channels 37 in which the door slides, are hinged inwards by means of the roller 41 together with the corresponding part of the jalousie on the axis 36. In this manner that part of the car construction 42 is no way interfered with. The (possibly) electrically driven roller 39 lies in a space not otherwise needed. The closing arrangement with its mechanism and operation involves no inconvenience to the passengers.

The construction of the girders and joints employs as far as possible the rules for light-construction because as already explained 40 the saving of weight is essential. As girders suited to the curves of the car surface are necessary they are made with curved flanges 43 or as tubes 44 (See Figs. 14-17). Only with such profiles is it possible (for 45 example) in the case of the outer ring-member of the cross frame 5 to fit to it the outer skin of the car shown by the line 45 the angle of which varies considerably at different points of the car, without having a 50 special profile at every point of the member. An open profile made up of two parts is shown in Figures 15 and 16. In this profile are shown holes 49 for lightness. Both parts 43 of Figs. 15 and 16 are joined by 55 plates 47 provided with bellmouthed holes 48 suited to the curvature of the flanges, the plates being spaced appropriately to the end thrust on the member. Fig. 17 shows a tube 44 provided with holes or slots 49 to 60 facilitate riveting. Since such slots in an ordinary tube would not have sufficient strength to prevent buckling at the edges the walls are strengthened by thickening as at 50 so that the inner-section has an approximately square form which is well

adapted to bending forces while the outer section of the girder is of almost circular form which is the most favourable struc- 70 section. The part of the tube through which the slots will be punched or drilled can be located by a channel 51 on the outside.

What we claim is:

1. A high-speed suspension railway car body having stream-line shape in its longitudinal direction and being of elliptical 75 shape in cross-section, the upper portion of said body being restricted in width similarly to a bottle-neck, and this restricted portion forming exteriorly a longitudinally continuous fin, substantially as set forth. 80

2. A high-speed suspension railway car body having stream-line shape in its longitudinal direction and being of elliptical shape in cross-section, the upper portion of said body being restricted in width similarly to a bottle-neck, and this restricted portion forming exteriorly a longitudinally continuous fin, the said body comprising elliptical members following one another in the axial direction of the body and produc- 85 90 ing together the streamline shape of the body, substantially as set forth.

3. A high speed suspension railway car body having stream-line shape in its longitudinal direction and being of elliptical 95 shape in cross-section, the upper portion of said body being restricted in width similarly to a bottle neck, and this restricted portion forming exteriorly a longitudinally continuous fin, the said body being com- 100 105 posed of interchangeable members elliptical in cross section following one another in the axial direction of the body and producing together the stream-line shape of the body, in combination with running suspension gears to which said interchangeable members are attached, substantially as set forth.

4. A high-speed suspension railway car body having stream-line shape in its longitudinal direction and being of elliptical 110 shape in cross-section, the upper portion of said body being restricted in width similarly to a bottle-neck, and this restricted portion forming exteriorly a longitudinally continuous fin, the said body being com- 115 120 posed of a plurality of interchangeable members elliptical in cross section shaped each as stated, including a portion of said fin, in combination with a corresponding plurality of running suspension gears to which said interchangeable members are attached, substantially as set forth.

5. A high-speed suspension railway train composed of cars each being of stream-line shape in its longitudinal direction and of elliptical shape in cross-section, the upper portion of said body being restricted in width similarly to a bottle-neck, and this restricted portion forming exteriorly a longitudinally continuous fin, in combination 125 130

- with coupling-rods adapted to resist buckling stress and with ball-joints and buffers arranged at the points of contact, substantially as set forth.
- 5 6. A high-speed suspension railway car, comprising, in combination, a car body having stream-line shape in its longitudinal direction and being of elliptical shape in cross-section, the upper portion of said body being restricted in width similarly to a bottle-neck, and this restricted portion forming exteriorly a longitudinally continuous fin, an air-propeller, and means for driving it, substantially as set forth.
- 10 7. A high-speed suspension railway car, comprising, in combination, a car body having stream-line shape in its longitudinal direction and being of elliptical shape in cross-section, the upper portion of said body being restricted in width similarly to a bottle-neck, and this restricted portion forming exteriorly a longitudinally continuous fin, an air-propeller at the head of said car-body and an air-propeller at the tail thereof; and means for driving them, substantially as set forth.
- 15 8. A high-speed suspension railway car, comprising, in combination, a car body having stream-line shape in its longitudinal direction and being of elliptical shape in cross-section, the upper portion of said body being restricted in width similarly to a bottle-neck, and this restricted portion forming exteriorly a longitudinally continuous fin; a main air-propeller and a subsidiary air-propeller; and means for driving them, substantially as set forth.
- 20 9. A high-speed suspension railway car, comprising, in combination, a car body having stream-line shape in its longitudinal direction and being of elliptical shape in cross-section, the upper portion of said body being restricted in width similarly to a bottle-neck, and this restricted portion forming exteriorly a longitudinally continuous fin; an air-propeller for starting the car and increasing moderately the starting speed, and a main air-propeller for full speed, the two propellers having different pitch, substantially as set forth.
- 25 10. A high-speed suspension railway car, comprising, in combination, a car body having stream-line shape in its longitudinal direction and being of elliptical shape in cross-section, the upper portion of said body being restricted in width similarly to a bottle-neck, and this restricted portion forming exteriorly a longitudinally continuous hollow fin; and running suspension gears for said car body, these gears being covered by said hollow fin, substantially as set forth.
- 30 11. A high-speed suspension railway car, comprising, in combination, a car body having stream-line shape in its longitudinal direction and being of elliptical shape in cross-section, the upper portion of said body being restricted in width similarly to a bottle-neck, and this restricted portion forming exteriorly a longitudinally continuous hollow fin, running suspension gears for the said car-body, and braking means therefor, said gears and means being enclosed in said hollow fin, substantially as set forth.
- 35 12. A high-speed suspension railway car, comprising, in combination, a car body having stream-line shape in its longitudinal direction and being of elliptical shape in cross-section, the upper portion of said body being restricted in width similarly to a bottle-neck, and this restricted portion forming exteriorly a longitudinally continuous hollow fin enclosing receptacles adapted to receive fuel, lubricant, cooling-water, and the like, substantially as set forth.
- 40 13. A high-speed suspension railway car body having stream-line shape in its longitudinal direction and being of elliptical shape in cross-section, the upper portion of said body being restricted in width similarly to a bottle-neck, and this restricted portion forming exteriorly a longitudinally continuous fin; the entire hull of said body being devised as a hollow lattice-work shell, substantially as set forth.
- 45 14. A high-speed suspension railway car body having stream-line shape in its longitudinal direction and being of elliptical shape in cross-section, the upper portion of said body being restricted in width similarly to a bottle-neck, and this restricted portion forming exteriorly a longitudinally continuous fin; the entire hull of said body being devised as a hollow lattice-work shell and its outer skin being of such a kind as to be adapted to stiffen said lattice-work, substantially as set forth.
- 50 15. A high-speed suspension railway car body having stream-line shape in its longitudinal direction and being of elliptical shape in cross-section, the upper portion of said body being restricted in width similarly to a bottle-neck, and this restricted portion forming exteriorly a longitudinally continuous fin, the entire hull of said body being devised as a hollow lattice-work shell and its outer skin forming substitute for the diagonals of said lattice-work, substantially as set forth.
- 55 16. A high-speed suspension railway car body having stream-line shape in its longitudinal direction and being of elliptical shape in cross-section, the upper portion of said body being restricted in width similarly to a bottle-neck and this restricted portion forming exteriorly a longitudinally continuous fin, the entire hull of said body being devised as a hollow lattice-work shell and its outer skin consisting of sheet-metal, substantially as set forth.
- 60 17. A high-speed suspension railway car

- body having stream-line shape in its longitudinal direction and being of elliptical shape in cross-section, the upper portion of said body being restricted in width similarly to a bottle-neck, and this restricted portion forming exteriorly a longitudinally continuous fin; the entire hull of said body being devised as a hollow lattice-work shell combined with transverse stiffening frames having each clear space in its middle part, substantially as set forth. 5
18. A high-speed suspension railway car body having streamline shape in its longitudinal direction and being of elliptical shape in cross-section, the upper portion of said body being restricted in width similarly to a bottle-neck, and this restricted portion forming exteriorly a longitudinally continuous fin; the entire hull of said body 15 being devised as a hollow lattice-work shell combined with transverse stiffening frames dividing the interior of said body into compartments, substantially as set forth. 20
19. A high-speed suspension railway car body having stream-line shape in its longitudinal direction and being of elliptical shape in cross-section, the upper portion of said body being restricted in width similarly to a bottle-neck, and this restricted portion 25 forming exteriorly a longitudinally continuous fin; and seats arranged in the longitudinal direction of said body along the interior wall-surfaces, substantially as set forth. 30
20. A high-speed suspension railway car body having stream-line shape in its longitudinal direction and being of elliptical shape in cross-section, the upper portion of said body being restricted in width similarly to a bottle-neck, and this restricted portion forming exteriorly a longitudinally continuous fin; and seats arranged in the longitudinal direction of said body along the interior wall-surfaces, and baggage-carrying means provided above, said seats, substantially as set forth. 35
21. A high speed suspension railway car body having stream-line shape in its longitudinal direction and being of elliptical shape in cross-section, the upper portion of said body being restricted in width similarly to a bottle-neck, and this restricted portion forming exteriorly a longitudinally continuous fin; seats arranged in the longitudinal direction of said body along the interior wall surfaces, and longitudinal girders located below the seats and contributing to support them, substantially as set forth. 50
22. A high-speed suspension railway car body having stream-line shape in its longitudinal direction and being of elliptical shape in cross-section, the upper portion of said body being restricted in width similarly to a bottle-neck, and this restricted portion forming exteriorly a longitudinally continuous fin; door-forming lateral openings in said body, and a lattice-work provided within said fin, substantially as set forth. 55
23. A high-speed suspension railway car body having stream-line shape in its longitudinal direction and being of elliptical shape in cross-section, the upper portion of said body being restricted in width similarly to a bottle-neck, and this restricted portion forming exteriorly a longitudinally continuous fin; door-forming lateral openings in said body, and a lattice-work provided within said fin, substantially as set forth. 60
24. A high-speed suspension railway car body having stream-line shape in its longitudinal direction and being of elliptical shape in cross-section, the upper portion of said body being restricted in width similarly to a bottle-neck, and this restricted portion forming exteriorly a longitudinally continuous fin, door-forming lateral openings in said body; and a lattice-work provided within said fin and being devised to form a continuous longitudinal stiffening for the said body, substantially as set forth. 65
25. A high-speed suspension railway car body having stream-line shape in its longitudinal direction and being of elliptical shape in cross-section, the upper portion of said body being restricted in width similarly to a bottle-neck, and this restricted portion forming exteriorly a longitudinally continuous fin; door-forming lateral openings in said body; a lattice-work provided within said fin; and rigid means connecting the said body with the running gear, substantially as set forth. 70
26. A high-speed suspension railway car body having stream-line shape in its longitudinal direction and being of elliptical shape in cross-section, the upper portion of said body being restricted in width similarly to a bottle-neck, and this restricted portion forming exteriorly a longitudinally continuous fin; door-forming lateral openings in said body; a lattice-work provided within said fin, and rigid means connecting the said body with the running gear and the brake-work, substantially as set forth. 75
27. A high-speed suspension railway car body having stream-line shape in its longitudinal direction and being of elliptical shape in cross-section, the upper portion of said body being restricted in width similarly to a bottle-neck, and this restricted portion forming exteriorly a longitudinally continuous fin; window-forming openings in the sidewalls of the said body; and diagonal bonds arranged in the proximity of said 80

window-openings, substantially as set forth.

28. A high-speed suspension railway car body having stream-line shape in its longitudinal direction and being of elliptical shape in cross-section, the upper portion of said body being restricted in width similarly to a bottleneck, and this restricted portion forming exteriorly a longitudinally continuous fin; seats arranged in the longitudinal direction of said body along the interior wall surfaces, longitudinal girders located below the seats, consisting of profile-bars having rounded-off legs and contributing to support said seats, substantially as set forth.
- 10 29. A high-speed suspension railway car body having stream-line shape in its longitudinal direction and being of elliptical shape in cross-section, the upper portion of said body being restricted in width similarly to a bottle-neck, and this restricted portion forming exteriorly a longitudinally continuous fin; seats arranged in the longitudinal direction of said body along the interior wall surfaces, longitudinal girders located below the seats; and consisting of pairs of profile-bars having rounded-off legs, and of perforated and flanged sheet-metal members connecting said bars with one another in appropriate distances, substantially as set forth.
- 15 30. A high-speed suspension railway car body having stream-line shape in its longitudinal direction and being of elliptical shape in cross-section, the upper portion of said body being restricted in width similarly to a bottle-neck and this restricted portion forming exteriorly a longitudinally continuous fin, seats arranged in the longitudinal direction of said body along the interior wall surfaces; and longitudinal girders located below the seats; and consisting of perforated tubes, the rims of the tube-holes being reinforced, substantially as set forth.
- 20 31. A high-speed suspension railway car body having stream-line shape in its longitudinal direction and being of elliptical shape in cross-section, the upper portion of said body being restricted in width similarly to a bottle-neck, and this restricted portion

forming exteriorly a longitudinally continuous fin; door-forming lateral openings in said body; door-forming flaps and horizontal hinges connecting said flaps with the body, the shape of each flap corresponding exactly to the outer shape of the said body, substantially as set forth.

32. A high-speed suspension railway car body having stream-line shape in its longitudinal direction, and being of elliptical shape in cross-section, the upper portion of said body being restricted in width similarly to a bottle-neck, and this restricted portion forming exteriorly a longitudinally continuous fin; door-forming lateral openings in said body shiftable walls adapted to close said door-forming openings; and guide means for these walls, substantially as set forth.

33. A high-speed suspension railway car body having stream-line shape in its longitudinal direction and being of elliptical shape in cross-section, the upper portion of said body being restricted in width similarly to a bottle-neck, and this restricted portion forming exteriorly a longitudinally continuous fin; door-forming lateral openings in said body; shiftable shutter-walls arranged to be adapted for use as doors for said openings; and guide means for these walls, substantially as set forth.

34. A high-speed suspension railway car body having stream-line shape in its longitudinal direction and being of elliptical shape in cross-section, the upper portion of said body being restricted in width similarly to a bottle-neck, and this restricted portion forming exteriorly a longitudinally continuous fin; door-forming lateral openings in said body; shiftable shutter-walls arranged to be adapted for use as doors for said openings; and guide-bars for these walls, these bars being hinged to the said body and adapted to be swung inwards, substantially as set forth.

In testimony whereof we affix our signatures.

FRANZ KRUCKENBERG
FRITZ GENTZCKE.
